UNITED STATES PATENT OFFICE.

GEORGE L. HINMAN, OF NEW HAVEN, CONNECTICUT, ASSIGNOR, BY MESNE ASSIGNMENTS, TO THE BATES MANUFACTURING COMPANY, OF ORANGE, NEW JERSEY, A CORPORATION OF NEW JERSEY.

DESIGN FOR A TELEPHONE INDEX.

Application filed February 23, 1924. Serial No. 8,701. Term of patent 14 years.

To all whom it may concern:

Be it known that I, GEORGE L. HINMAN, a citizen of the United States, residing at New Haven, county of New Haven, and State of Connecticut, have invented a new, original, and ornamental Design for Telephone Indexes, of which the following is a description, reference being had to the accompanying drawing, forming a part thereof.

The figure is a perspective view of a telephone index showing my new design.

I claim:

The ornamental design for a telephone index as shown.

GEORGE L. HINMAN.
